(57) **CLAIM**

The ornamental design for a "temperature probe hub," as shown and described.

DESCRIPTION

FIG. 1 is a front right perspective view of a temperature probe hub for use with a cooking apparatus.

FIG. 2 is a bottom left perspective view of the temperature probe hub of FIG. 1.

FIG. 3 is a front view of the temperature probe hub of FIG. 1.

FIG. 4 is a rear view of the temperature probe hub of FIG. 1.

FIG. 5 is a right side view of the temperature probe hub of FIG. 1.

FIG. 6 is left side view of the temperature probe hub of FIG. 1.

FIG. 7 is a top view of the temperature probe hub of FIG. 1.

FIG. 8 is a bottom view of the temperature probe hub of FIG. 1; and,

FIG. 9 is another front view of the temperature probe hub of FIG. 1.

The features shown in broken lines form no part of the claimed design.

(Continued)

The lighter solid lines denote surfaces and contours. Line shading is not surface ornamentation.

1 Claim, 7 Drawing Sheets
